SHEET HANDLING MECHANISM

Application filed August 5, 1925. Serial No. 48,227.

This invention relates to certain improvements in mechanism for handling webs of varying widths and sheets cut therefrom.

The usual method of handling webs of varying widths and the sheets cut therefrom in a flat or pile delivery is to run a web, after printing, through a pair of forwarding rolls to and through a pair of cutting cylinders by which a sheet is cut from the web. This sheet is then taken at its front or leading edge by grippers which are carried on shafts secured to chains, the grippers taking the sheet to a position above the pile and dropping it on the pile. This mechanism for handling sheets of varying widths has certain disadvantages. In order to allow the grippers to act without interfering with the tail of the preceding sheet, the sheets must be a certain distance apart. To get this space between the sheets it is necessary to speed up the sheets, after they are cut, or to provide a collecting mechanism where the product is of such character that it can be collected, this collecting providing the space between the collected sheets. Furthermore, this method of handling sheets requires a run of considerable length between the press and the pile, thereby increasing the danger of smutting the sheets and, as the sheets have to be cut before they are received by the grippers, the sheets are not always under positive control and trouble may be experienced owing to the chokes in the run of the sheets. This way of handling the sheets by their front edges requires, in addition, a considerable amount of expensive mechanism in order to get the sheets into the position where they can be taken by the grippers.

It is the especial object of the present invention to provide a mechanism whereby the web is always under positive control of the grippers, as are the sheets cut therefrom, these grippers being arranged to take the web by its side edges before it is cut and to keep it under control until it is released for delivery.

It is a further object of the invention to produce a construction for delivering sheets on a pile which shall simplify the mechanism necessary, thereby reducing the cost of con-

struction of the machine and providing a construction by which the run of the product from the press to delivery, is shortened so as to reduce the danger of smutting.

With these and other objects not specifically referred to, the invention consists in certain novel parts, arrangements and combinations which will be described in connection with the accompanying drawings and the novel features pointed out in the claims hereunto annexed.

Referring to these drawings:

Figure 1 is a diagrammatic, partly broken away, side view of so much of a delivery mechanism as is necessary for an understanding of the invention;

Figure 2 is an enlarged, cross-sectional view, the section being taken on line A—A of Figure 1 looking in the direction of the arrow;

Figure 3 is an enlarged detail sectional view, partly broken away, of the cutting cylinders; and

Figure 4 is a plan view of one side of the construction shown in Figure 2, the view being taken looking in the direction of arrow 4 of that figure.

Referring now to these drawings in detail, the machine selected to illustrate the invention is the delivery end of a printing press, not shown, in which the sheets are delivered flatwise in a pile. It will be understood that the sheets may be delivered flatwise to a final delivery which is not a pile and the invention is, therefore, not to be restricted to such piling of the sheets.

In the particular construction shown, the parts are supported in suitable framing *a*, *b*, which may be of any usual or desired configuration. The web marked 1 may be led directly from the press between a pair of forwarding rolls 2, 3, and over to guides 4 where the side edges of the web are seized by grippers indicated generally by numeral 5 and hereinafter more specifically referred to. These grippers are carried on gripper shafts 6 extending across the machine and mounted at each end in blocks 8 which form a part of certain of the links of chains 7.

The chains 7 may be constructed and

driven in any suitable manner. As shown, the chains at one end pass over sprockets 9 carried on a driving shaft 10 which extends widthwise of the machine, being suitably supported in the side frames of the machine. Only one of these sprockets is shown, but it is understood the construction is duplicated on the other side of the mechanism. At the other end the chains pass over sprockets 11, one of which is shown, mounted on studs 12 suitably supported in the side frames, these studs, in the best construction, being adjustable in slotted extensions 12' so that the tension of the chains may be readily regulated. In the best construction, furthermore, suitable guides or supports for the chains are provided, these supports being shown in the form of bars 13, 14, over which the chains pass and a bar 15 under which they pass. With this construction the chains are suitably supported and guided in the machine.

In accordance with the invention, means are provided whereby the grippers are opened to take the web by its side edges and closed to forward the web, a sheet being cut from the web while under control of the grippers, and means are also provided to open the grippers to release the cut sheet after it has reached the delivery point. While this means may be somewhat varied, in the particular construction shown the grippers are adjustable sidewise on the shafts so that they can handle webs and sheets of widely varying widths. The grippers are opened by means of a cam 16 which is supported on the shaft 10 and on a rod 17, this cam being slidable widthwise of the shaft and rod so that it can be positioned to open the grippers no matter at what point on the shaft they may be. The grippers are closed by a spring 16', being opened against the spring by the cam. The grippers are opened to release the sheet at the proper point, by means of a cam 18 supported on and slidable widthwise of a rod 19.

In machines embodying the invention in the best form, a sheet will be cut from the web and this cutting operation will be effected while the sheet is under control of the grippers. While the particular cutting mechanism may vary, the cutting mechanism will be such that the grippers can pass through the cutting mechanism so that they will always have control of the sheet. While the particular cutting mechanism may, of course, be varied to some extent, in the particular construction shown there are provided a pair of cutting cylinders 21, 22, mounted on shafts 23, 24, supported in pillow blocks 23', 24'. In the particular construction illustrated, these cutting cylinders are provided with cutting knives 25, 26, suitably secured to webs 26' by means of bolts 26'', these knives operating to produce a shear cut. It

will be understood, of course, that any other suitable or desirable cutting mechanism may be substituted for this described. In order that the grippers may pass through the cylinders while yet retaining their grip on the sheets, the cylinders are cut out, as shown in Figure 3, at each end, leaving spaces indicated by the numerals 100, 101 which permit free passage of the grippers and the shafts.

The cut sheets are carried by the grippers to the final delivery which, in the present instance, is a pile delivery, the delivery board of which is marked 20, the grippers being opened by the cam 18 so as to drop the sheet on this delivery board.

The tail of the sheet is controlled so that it is out of the way of a following sheet. While various constructions may be used for effecting this, there is, as shown, a striker bar 27 supported in a holder 28 which rotates on a shaft 29 suitably supported in the side frames of the machine. If desired, additional strikers in the form of fingers 30 carried in arms 30' on a rock shaft 31 may be provided for striking down the sheet so as to free it from the grippers. The rock shaft 31 is operated to raise and lower the strikers by means of an arm 102 carrying a forked rod 103 provided with a cam roll 104 which is operated by a cam 32 on the shaft 29, before referred to. With this construction the sheet is cleared from the grippers and it is struck down out of the way of a succeeding or following sheet.

In machines embodying the invention in its best form, the sheets are front registered against a stop 33 carried on a shaft 34 suitably supported in the machine frames. The tail end of the sheet is jogged or pushed against this front stop by means of a jogger 35 carried on a shaft 36 suitably supported in the side frames of the machine, which is operated by a cam, not shown, on a cam shaft 37 by means of an arm 39 and a forked rod 38 indicated by broken line in Figure 1.

In the best construction, the sheets will also be side-jogged, that is, evening devices are employed for evening up the sheets sidewise of the pile and these joggers are arranged so that they can be used for different width sheets. While the specific construction of these evening devices may be somewhat varied, in the particular construction illustrated there is provided, on the shaft 36 before referred to, lever arm 40, into which is connected a rod 41. The other end of this rod is connected to a lever arm 42 carried on a rock shaft 43 (see Fig. 2), this shaft 43 extending lengthwise of the machine. This shaft 43 has secured thereto a second lever arm 44 which works between a pair of collars 45, 46 on a sleeve 49. This sleeve has a stem 50 formed with a side jogger 51. The collar 45 is, as shown, a split collar provided with a clamping device such

as a bolt 45' by which the collar may be adjusted at any point of the machine widthwise, as desirable. This sleeve, it will be observed, is oscillated by the lever arm 44 working between the collars 45, 46 and, in the best construction, coiled springs 47, 48, are provided against which the arm 44 is oscillated. The sleeve is supported in any suitable manner, as in a bearing 110 in one of the side frames before referred to, and a bearing 111 carried by a bracket arm 112 suitably secured as at 113 to the side frames before referred to.

The other side of the machine is also provided with a similar jogger 58 and, in the best construction, the joggers are arranged in pairs, being marked 51a, 58a. These joggers are mounted to operate simultaneously. In the particular construction shown for doing this, the rock shaft 43 is provided with a lever arm 52 which, through a rod 53, connects with a lever arm 54 on the other side of the machine, this arm 54 being carried on a shaft 54' provided with a gear 55. This gear 55 meshes with a gear 56 on a rock shaft 57. The operation of the parts is thus simultaneous and the sheets are piled or evened along their sides.

The gripping mechanism by which the side edges of the web is taken may be varied widely in construction. That shown, however, is a convenient one and will be the same for all the grippers. As illustrated, this mechanism includes a holder 61 having an extension 62. This holder is, as shown, split and is clamped on the shaft 6, before referred to, by a bolt 62', by loosening which the holder may have a sliding movement on the shaft, being keyed to the shaft by a key or feather 63. This holder is provided with another extension 64 which carries a stud 65 on which the movable gripper finger 66 is pivoted. One end of the pivoted finger 66 extends under the extension 62 of the holder 61 and is normally pressed in a gripping relation therewith by the spring 16', before referred to. The opposite end of the pivoted gripper finger carries a cam roll 68 which engages the cams 16, 18, before referred to, by which the grippers are opened.

With the construction shown and described mechanism has been provided for handling webs or sheets of widely varying width, one in which a great deal of mechanism may be omitted thereby providing a simple and consequently cheap structure, and one in which the web and the sheet is under positive control of the grippers until released for final delivery. With this construction no spacing is necessary, the sheets following each other in regular succession thereby speeding up the delivery and, as the sheets are always positively controlled by the grippers, there is no danger of chokes or missed sheets.

While the invention has been shown and de-

scribed in its preferred form, it will be understood that certain changes in the character of the cutting mechanism, gripping mechanism, etc. may be made without departing from the invention as defined in the appended claims. 70

What is claimed is:

1. In a delivery, the combination of means for forwarding a web, from which a sheet is to be cut, sheet forwarding grippers arranged to take the web by its side edges, means for adjusting the grippers widthwise of the sheet path to take sheets of different widths, a receiver to which the cut sheet is forwarded by the grippers, and means for clearing the tail of a sheet from the head of a succeeding sheet. 80

2. In a delivery, the combination of means for forwarding a web from which a sheet is to be cut, sheet forwarding grippers arranged to take the web by its side edges, means for adjusting the grippers widthwise of the sheet path to take sheets of different widths, a receiver to which the cut sheet is forwarded by the grippers, and means for freeing the body of the sheet from the grippers. 85

3. In a delivery, the combination of means for forwarding a web from which a sheet is to be cut, sheet forwarding grippers arranged to take the web by its side edges, means for adjusting the grippers widthwise of the sheet path to take sheets of different widths, a receiver to which the cut sheet is forwarded by the grippers, means for clearing the tail of a sheet from the head of a succeeding sheet, and means for freeing the body of the sheet from the grippers. 95

4. In a delivery, the combination of means for forwarding a web from which a sheet is to be cut, a guide closely adjacent the forwarding means, sheet taking grippers arranged to take the web by its side edges, travelling supports for the grippers, means for opening the grippers to take the web, a receiver, means for opening the grippers to deliver the sheet, and means for adjusting the grippers and the gripper controlling mechanism independent of the supports widthwise of the sheet path to take sheets of different widths. 110

5. In a delivery, the combination of a travelling gripper carrier, shafts on the carrier, grippers slideable on the shafts widthwise of the sheet path and arranged to take a web from which a sheet is to be cut by its side edges, cam shafts, and cams slideable on the shafts widthwise of the sheet path for opening the grippers. 115

6. In a delivery, the combination of a pair of carrier chains, blocks carried by the chains, shafts mounted in the blocks, grippers clamped on the shafts and slideable thereon widthwise of the sheet path and arranged to take a web from which a sheet is to be cut by its side edges, cam shafts, and cams adjustable on the shafts widthwise of the sheet path for opening the grippers. 125

7. In a delivery, the combination of a travelling gripper carrier, shafts on the carrier, grippers slideable on the shafts widthwise of the sheet path and arranged to take a web from which a sheet is to be cut by its side edges, cam shafts, cams slideable on the shaft widthwise of the sheet path for opening the grippers, a striker finger for striking down the tail of a sheet, and striker fingers for striking the body of a sheet and freeing it from the grippers as it is delivered.

8. In a delivery, the combination of means for forwarding a web, a web guide closely adjacent the forwarding means, a travelling gripper carrier extending over the guide, shafts on the carrier, grippers slideable on the shafts widthwise of the web path and arranged to take a web from which a sheet is to be cut by its side edges from the guide, cam shafts, and cams slideable on the shaft widthwise of the sheet path for opening the grippers.

9. In a delivery, the combination of a travelling gripper carrier, transverse supports on the carrier, grippers slideable on the support widthwise of the sheet path independently of the carrier and arranged to take a web from which a sheet is to be cut by its side edges, cam supports, cams slideable on the supports widthwise of the sheet path for opening the grippers, and a receiver for receiving the sheet.

10. In a delivery, the combination of a pair of chains, shafts supported between the chains, grippers slideable on the shafts widthwise of the sheet path independently of the chains and arranged to take a web from which a sheet is to be cut by its side edges, cam shafts, cams slideable on the shafts widthwise of the sheet path for opening the grippers, and a receiver for receiving the sheet.

11. In a sheet delivery, a travelling gripper carrier, supports on the carrier, grippers secured to the supports and arranged to seize a web from which a sheet is to be cut by its side edges, and means for adjusting the position of the grippers relatively to the carrier and transversely to the path of the sheet.

In testimony whereof, I have hereunto set
50 my hand.

ADOLPH M. ZUCKERMAN.
